UNITED STATES PATENT OFFICE.

GUSTAV J. E. STEUBER, OF KANSAS CITY, MISSOURI.

MITER-CLAMP.

1,201,888.

Specification of Letters Patent. Patented Oct. 17, 1916.

Application filed January 28, 1916. Serial No. 74,902.

To all whom it may concern:

Be it known that I, GUSTAV J. E. STEUBER, a citizen of the United States, residing at 2625 Bellefontaine avenue, Kansas City, in 5 the county of Jackson and State of Missouri, have invented new and useful Improvements in Miter-Clamps, of which the following is a specification.

This invention relates to a clamp which 10 may be applied to the sections of a miter for holding said sections in mitered relation irrespective of the miter or length of the sections.

The primary object of the invention is to 15 provide a clamp with hingedly connected spacing members removably and slidably mounted upon the attaching bars of the clamp which may be connected with the respective sections of the miter so that when 20 said sections are held in mitered relation by the clamp the sections may be swung in opposite directions to separate the joint sufficiently far to enable glue to be placed upon the side edges thereof.

Another object of the invention is to provide 25 clamping arms for the clamp so constructed that they may be connected with the attaching bars of the clamp after the same have been applied to the respective sections 30 of the miter.

A still further object of the invention is to provide the clamp with L-shaped supporting members having grooved ends which may be arranged to receive the attaching 35 bars of the clamp after said bars have been secured to the respective sections of the miter to prevent the sagging of said bars when the clamping arms of the clamp are in clamping engagement with the sections 40 of the miter.

A still further object of the invention is to provide the clamp with attaching bars having rabbeted side edges which are recessed at intervals throughout the length of 45 said bars to enable the spacing members, clamping arms and the supporting bars to be engaged with the attaching bars after the same have been applied and clamped to the respective sections of the miter.

With these and other objects in view the 50 invention resides in the novel combination and arrangement of parts, which will be herein after described, and particularly pointed out in the claims.

The preferred form of the invention has 55 been illustrated in the accompanying draw-

ing, although no restriction is necessarily made to the precise details of construction therein shown, as changes, alterations and modifications within the scope of the claims 60 may be resorted to when so desired.

In the drawing: Figure 1 is a detail perspective view of the improved clamp showing the same applied to a miter, Fig. 2 is a vertical transverse sectional view on the 65 line 2—2 of Fig. 1 looking in the direction of the arrow, Fig. 3 is a view similar to Fig. 2 to better illustrate the construction of the clamping arms. Fig. 4 is a view similar to Fig. 3 to more clearly illustrate the construction of the supporting members used in connection with the clamp, Fig. 5 is a side elevation of one of the attaching bars of the clamp showing the same removed from the miter and having the spacing members, clamping arms and supporting members disconnected therefrom.

Like characters of reference denote corresponding parts throughout the several views in the drawing in which the numeral 1 80 designates the sections of the miter which are joined, as at 2 to complete the miter joint.

Arranged upon opposite sides of the sections 1 are attaching members 3, each comprising a bar 4 having rabbeted side edges 5 which, are provided at spaced intervals throughout the length of the bar with notches 6 while slidably mounted upon the bars 4 are sleeves 7.

The sleeves 7 are shaped to correspond to the shape of the bars 4 which they encircle and have a portion thereof snugly fitting within the rabbeted portion of said bars, while depending from the under side 95 of the sleeves and spaced therefrom for a greater portion of their length are arms 8 the free ends of which are provided with set screws 9. The sleeves 7 are recessed on their under side, as indicated at 10 so that, a portion of the bars 4 disposed in said sleeve will contact with the sections of the miter when the bars are positioned thereon with the ends of the sections disposed between the arms and the sleeves, thus it will be seen 105 that when the set screws 9 are tightened one end thereof will bear against the under side of said sections and force the same into contact with the bars thus holding the bars positioned upon the sections and the sleeves 110 securely clamped between the bars.

Spacing members 11 are provided for con-

nection with the bars 4 and each comprise a companion section 12 and 13, each of said sections having an end grooved to receive the bars 4 with the side walls of the grooves recessed to snugly fit within the grooves in the rabbeted sides of said bars, said grooves being designated by the numeral 14. Each of the companion members 12 and 13 have the end thereof distant from the grooved end bent to lie in offset relation with the body of said members. When the bars 4 are in clamping position upon the sections the offset ends of said members will overlap and enable a stud 15 in the end of the offset portion of the member 13 to be positioned within a groove in the end of the offset portion of the section 12 whereby, the said sections are removably and hingedly connected. Through the above described construction of the spacing members it will be seen that when the sections thereof are applied to the clamping bars 4 the said bars may be spaced a suitable distance from the mitered edge of the sections and then clamped to said sections in such a manner as to cause the stud 15 on the sections 13 to be positioned within the grooves 16 in the section 12 thus enabling the sections of the miter to be swung apart a sufficient distance to permit glue to be inserted upon the mitered edges of said sections and upon swinging the sections in the reverse direction the mitered edges thereof will be caused to contact and held in such relation through the connection of the spacing members with the attaching bars of the clamp.

In order that the sections of the miter may be held in contacting relation until the glue sets clamping arms 17 are provided each of which comprises companion sections 18 and 19 and each section of the clamping arms has an end provided with a groove similar to the groove in the end of the spacing members and designated by the numeral 20. Each section 18 of the clamping arms has its end distant from that containing the groove 20 provided with a curved finger 21, the free end of which is provided with a set screw 22 so that when the sections 18 and 19 of the clamping arms 17 are in clamping position upon the bars 4 the set screws may be tightened to have one end thereof bear in notches 23 in the ends of the sections 19 of the clamping arms thus securing the arms in clamping position upon the sections of the miter.

When it is desired to use the clamp for holding miter sections of considerable length in mitered relation it has been found desirable to provide supporting members for the bars 4 which in this instance have been shown to comprise L-shaped members designated by the numeral 24, said members having their free ends provided with grooves 25 similar to the grooves in the ends of the clamping

arms 17 and the spacing members, said members when engaged with the bars 4 serving to prevent the bulging or spreading of the bars when the set screws 22 carried by the fingers on the sections 18 of the clamping arms are tightened to cause the mitered ends of the mitered sections to contact.

When it is desired to apply the clamp to a miter the sleeves 7 on the bars 4 are adjusted a sufficient distance apart to enable the ends of the sections to be positioned between the bars and the arms on the sleeves, in this position the set screws 9 are tightened to lock the bars in contacting relation with the miter sections and the sleeves against sliding movement upon the bars. The sections 12 and 13 of the spacing members are now connected with the bars 4 by engaging the grooved ends of said bars with the respective sections through the recesses 6 in the bars 4, said sections being moved longitudinally along the bars 4 until the stud 15 in the sections 13 of the spacing members are received in the grooves 16 in the sections 12 of said member. After the above described operation has been completed it will be noted that the mitered sections may be swung to a position to enable glue to be placed upon their mitered faces and that the bars 4 are spaced an equal distance from the mitered faces throughout their entire length to facilitate the proper adjustment of the clamping arms and supporting members as heretofore described. After the glue has been spread upon the mitered faces of said sections the sections may again be swung to position which will cause the mitered faces of said sections to contact and sections 18 and 19 of the clamping arms 17 connected with the bars 4 by means of the recesses 6, said sections being slid longitudinally of the bars between the notches or recesses until a point is reached where it is desired to apply pressure to the miter joints by means of the clamping arms. The set screws 22 are now tightened so that the ends of the screws bear in the grooves 20 in the sections 19 thus forcing the clamping arm sections in clamping engagement with the miter sections. It will of course be understood that any number of clamping arms may be employed for this purpose as found desirable and that if the miter sections are of considerable length a sufficient number of supporting members may be connected with the bars by engaging the grooved ends of said members with the bars by means of the recesses 6.

From the above statement it will be seen that the spacing members 11 space the bars 4 the desired distance from the mitered edges of the sections throughout their entire length so that, when the clamping arms are applied to the bars the ends of the set screws 22 will register with the recesses of grooves 20 in the members 19 and that sup-

porting members prevent the spreading or sagging of the bars 4 when the clamping arms are in clamping engagement with the miter sections, thus insuring a perfect joint 5 at the meeting faces of the miter sections.

It will be further noted that by providing the bars 4 with the alined recesses 6 in the side edges thereof and providing the sections of the clamping arms and spacing 10 members with grooves snugly receiving the bars 4 the said spacing members and clamping arms and also the supporting members may be applied or detached from the bars 4 after the same have been positioned upon 15 the miter sections.

From the foregoing statements taken in connection with the accompanying drawing it is at once apparent that a miter clamp has been provided, which is inexpensive of man- 20 ufacture, simple in construction and highly efficient in use.

Having described the invention what is claimed is:

1. A miter clamp comprising attaching 25 bars, hingedly connected spacing members removably mounted upon the bars, clamping arms detachably connected with said bars and mounted to slide thereon, and supporting members having grooved ends slidably 30 engaged with said bars.

2. A miter clamp comprising hinged spacing members having grooved ends, bars having rabbeted side edges snugly fitting in the grooved ends of the spacing members, 35 clamping arms removably and slidably mounted upon said bars, L-shaped supporting members carried by said bars, sleeves mounted to slide on said bars, arms on said sleeves, and clamping elements carried by 40 said arms.

3. A miter clamp having bars provided with rabbeted side edges and recessed at intervals throughout the length of the bars, sleeves mounted to slide on said bars, clamp- 45 ing elements carried by the sleeves, spacing members having grooved ends for connection with the bars, offset portions upon the

spacing members, and means for hingedly connecting the offset portions of said members.

4. A miter clamp having bars provided with rabbeted side edges recessed at intervals throughout the length of the bars, clamping means removably mounted upon the bars, spacing members having sections 50 carried by the respective bars and provided with overlapping ends, the sections of the spacing members upon one of said bars having grooves, and studs upon the overlapping ends of the sections upon the other bar 55 adapted to fit in the grooves in the ends of the first mentioned sections.

5. A miter clamp having bars provided with rabbeted side edges provided at intervals throughout the length of the bars with 60 alined recesses, clamping arms comprising sections having grooved ends removably connected with the respective bars, fingers upon the sections upon one of said bars, and clamping screws carried in the ends of said 65 fingers and adapted to contact with the sections upon the other bar whereby, the clamping arms are held in clamping position.

6. A miter clamp having spacing members each including hingedly connected companion sections having grooves in the ends thereof provided with rabbeted side walls, clamping members each comprising companion sections having grooved ends provided with rabbeted side walls, clamping 75 bars having channeled side edges adapted to fit snugly within the grooves in the sections of the spacing members and clamping arms, said side walls of the bars being provided with recesses at spaced intervals whereby, 80 the sections of the spacing members and clamping arms may be removed therefrom when said bars are in clamping position.

In testimony whereof I affix my signature in presence of two witnesses.

GUSTAV J. E. STEUBER.
